UNITED STATES PATENT OFFICE.

RICHARD M. DAVIS, OF WEST PITTSTON, PENNSYLVANIA.

DEFLECTOR FOR GASOLINE-HOSE NOZZLES.

Application filed August 1, 1927. Serial No. 209,748.

My invention relates to gasoline hose nozzles for automobile filling stations, and particularly to a shield or deflector for the mouth of the nozzle.

It is customary at automobile filling stations to hang the nozzle of the gasoline hose, when not in use, so that the mouth of the nozzle opens upwardly. This permits rain, snow or hail to enter the mouth of the nozzle and accumulate more or less in the hose. For this reason, careful drivers refuse to refill their gasoline tanks in bad weather at stations having unprotected nozzles.

The object of my invention is to provide a deflector for the mouth of gasoline hose nozzles which will effectually prevent moisture and dirt from entering the nozzle, when the same is hung in its usual position when not in use. Further objects of my invention are, to provide a device as mentioned which will be of simple construction, of low cost to manufacture, which may be readily installed on any gasoline nozzle, and which will be automatic in its operation of closing its nozzle when not in use, and opening the same to permit a free flow of gasoline therefrom when the end of the nozzle is inverted and placed within a tank. Other objects will appear hereinafter.

With these objects in view my invention consists generally in a deflector for the purpose mentioned comprising a head adapted to cover the mouth of the nozzle and a stem on the head extending into the nozzle and provided with a longitudinal slot to receive a pin for securing the device to the nozzle and permitting longitudinal movement of the deflector. My invention further consists in a device as mentioned in which said stem is tapered, with the root of the stem of substantially the same cross sectional area as the mouth of the nozzle, whereby the head will be properly seated on the end of the nozzle when the nozzle is hung in its usual position. My invention further consists in a gasoline hose nozzle in combination with a deflector as above mentioned. My invention further consists in various details of construction and combination and arrangements of parts all as will be fully described hereinafter and particularly pointed out in the claims.

My invention will be more readily understood by reference to the accompanying

drawings forming a part of this specification and in which—

Fig. 1 is a longitudinal sectional view of a gasoline hose nozzle illustrating the same in the position it assumes when in inoperative position, and equipped with a deflector embodying my invention, and

Fig. 2 is a longitudinal sectional view of the same in the position it assumes when filling a tank.

Referring now to the drawings, 1 indicates the usual gasoline hose nozzle having the hook 2 for supporting the same when not in use. The nozzle is provided with the usual bore 3 terminating in the mouth 4. These portions of the device are old and I make no claim to the same except in combination with the deflector hereinafter described.

The deflector comprises a head 5 having a base 6 of sufficient area to entirely cover the end of the nozzle when the device is in the position shown in Fig. 1, and a stem 7 preferably formed integrally therewith. The stem 7 is provided with a longitudinal slot 8 through which extends a pin 9 having its ends fixed in the walls of the nozzle. This slot and pin arrangement provides a permanent connection of the deflector with the nozzle, and permits free movement of the deflector from open to closing positions, and vice versa. The stem 7 is preferably tapered with the root 10 thereof, adjacent the head 5, being of substantially the same cross sectional area as the mouth 4 of the nozzle, so that the stem will accurately position the head 5 when the nozzle is raised into the position shown in Fig. 1. The head 5 is suitably formed to shed moisture, such as rain, snow or hail, and to this end is preferably semi-spherical, as illustrated.

When the nozzle is lowered to fill a tank, as illustrated in Fig. 2, the deflector will automatically drop into the position shown in said figure. This, together with the taper of the stem 7, will open the nozzle sufficiently to permit a free flow of gasoline. To minimize any resistance of the end of the stem to the free flow of the gasoline, the end of the stem is preferably rounded as indicated at 11.

I claim:

1. A gasoline hose nozzle in combination with a deflector therefor, comprising a head

adapted to fit over the end of the nozzle and a stem projecting into the nozzle, said stem being provided with a longitudinally disposed slot and a retaining pin extending through said slot, substantially as described.

2. A device as set forth in claim 1 in which the stem is tapered, and the root of

the stem adjacent the head is of substantially the same cross sectional area as the mouth of the nozzle, substantially as described.

In testimony whereof I have signed my name to this specification.

RICHARD M. DAVIS.
